UNITED STATES PATENT OFFICE.

MONROE GUETT, OF HARTFORD, CONNECTICUT, ASSIGNOR TO THE HART & HEGEMAN MANUFACTURING COMPANY, OF SAME PLACE.

DESIGN FOR A PUSH-BUTTON.

SPECIFICATION forming part of Design No. 28,648, dated May 17, 1898.

Application filed November 30, 1897. Serial No. 660,297. Term of patent 14 years.

To all whom it may concern:

Be it known that I, MONROE GUETT, a citizen of the United States, residing at Hartford, Connecticut, have invented and produced a new and original Design for a Push-Button, of which the following is a specification, reference being had to the accompanying drawings, forming a part thereof.

Figure 1 is a view of the front end of a push-button, showing my design. Fig. 2 is a side view of the same push-button, these two views being deemed essential to a proper understanding of the design which is the subject of the invention.

As shown in the drawings, the leading or material features of my design are the smooth cylindrical sides, with the star-shaped or approximately circular image, with an indented, notched, or serrated circumference on the cir-

cular front end of the button. The color or shade of the figure or image *a* is in contrast of the color or shade of the remaining portion *b* of the end of the button, so that the figure or image will be the conspicuous or salient feature of the end. The surface of the figure or image *a* and the surface of the remaining portion *b* of the end of the button are flush and smooth.

Having described my invention, what I claim as new, and desire to secure by Letters Patent, is—

The design for a push-button herein shown and described.

MONROE GUETT.
